(57) **CLAIM**

An ornamental design for a foldable foot measuring device, as shown and described.

DESCRIPTION

FIG. 1 is a front-left perspective view of a design for a foldable foot measuring device.

FIG. 2 is a back view of the foldable foot measuring device.

FIG. 3 is a front view of the foldable foot measuring device.

FIG. 4 is a right side view of the foldable foot measuring device.

FIG. 5 is a left side view of the foldable foot measuring device.

FIG. 6 is a top view of the foldable foot measuring device.

FIG. 7 is a bottom view of the foldable foot measuring device.

FIG. 8 is a front-left perspective view of the foldable foot measuring device in a partially folded configuration.

FIG. 9 is a back view of the foldable foot measuring device in the partially folded configuration.

FIG. 10 is a front view of the foldable foot measuring device in the partially folded configuration.

FIG. 11 is a right side view of the foldable foot measuring device in the partially folded configuration.

FIG. 12 is a left side view of the foldable foot measuring device in the partially folded configuration.

FIG. 13 is a top view of the foldable foot measuring device in the partially folded configuration.

FIG. 14 is a bottom view of the foldable foot measuring device in the partially folded configuration.

FIG. 15 is a left side view of the foldable foot measuring device in a folded configuration.

FIG. 16 is a right side view of the foldable foot measuring device in the folded configuration.

FIG. 17 is a top view of the foldable foot measuring device in the folded configuration; and,

FIG. 18 is a bottom view of the foldable foot measuring device in the folded configuration.
